UNITED STATES PATENT OFFICE.

JOHN A. LAMONT, OF CHICAGO, ILLINOIS, ASSIGNOR TO AMERICAN STEEL FOUNDRIES,
OF CHICAGO, ILLINOIS, A CORPORATION OF NEW JERSEY.

SIX-WHEEL EQUALIZING-TRUCK.

1,393,798.

Specification of Letters Patent. Patented Oct. 18, 1921.

Application filed July 18, 1921. Serial No. 485,433.

To all whom it may concern:

Be it known that I, JOHN A. LAMONT, a citizen of the United States, residing at Chicago, in the county of Cook and State of Illinois, have invented certain new and useful Improvements in Six-Wheel Equalizing-Trucks, of which the following is a specification.

This invention relates to a six-wheel equalizing truck.

One object of the invention is to provide a side frame and associated parts, which have relative vertical movements, with simple and efficient means for guiding such relative movements and avoiding difficulties caused by shrinkage involving such parts.

Another object is to provide a simple and efficient equalizing arrangement wherein a snubbing effect is given to the movement of equalizing levers and whereby the equalizing beam is maintained in its normal position or quickly returned thereto if moved therefrom.

Another object is to provide an equalizing arrangement adapted to meet the various requirements for successful commercial use.

These and other objects are accomplished by means of the arrangement disclosed on the accompanying sheets of drawings, in which—

Figure 1 is a fragmentary longitudinal sectional view, parts being shown in elevation, of a railway car truck embodying my invention;

Fig. 2 is a fragmentary top plan view of a side frame forming a part of my truck;

Fig. 3 is a sectional view taken in the plane of line 3—3 of Fig. 1; and

Fig. 4 is a sectional view taken in the plane of line 4—4 of Fig. 1.

The various novel features of the invention will be apparent from the following description and drawings and will be particularly pointed out in the appended claims.

Referring to the figures of the drawings, it will be noted that I have disclosed my invention in connection with a railway car truck including a side frame 10 having a central opening 11 extending through the top wall of the frame and down between the side walls thereof for the reception of equalizing parts associated with an intermediate journal box 12. The side frame in each case has spaced walls 13 between which, at the central part of the frame, are two spaced

H-shaped beams 14, the webs 15 and inner flanges 16 of which act as guides for a relatively vertical movable spring cap 17 having depending arms 18 which rest upon and bridge springs 19 mounted upon oppositely arranged brackets 20 formed on the journal box 12. The spring cap 17 more specifically has end walls 21 which directly cooperate with the webs 15 and inner flanges 16 of the H-shaped beams 14 for guiding the relative vertical movements between the spring cap and side frame. These H-shaped beams, which are separate elements secured to the side walls 13 of the side frame, are of definite dimensions, are secured in place in the side frame in any suitable manner such as by rivets 22, and are not subject to shrinkage variations such as those caused by tied portions formed integrally with the side walls of the side frame and bridging same. At the same time the H-shaped beams have relatively smooth surfaces whereby friction is reduced to a minimum, which is not so true of castings. The cap 17 is provided with a centrally arranged groove 23 in which an equalizing beam 24 is pivoted, the outer ends of said equalizing beam curving downwardly and being provided with grooves in which pins 25 are located for the reception of the inner ends of gooseneck shaped equalizing levers 26. The outer ends of these equalizing levers are pivotally supported by the side frames, as at 27. Bolster members 28 rest upon intermediate portions of the equalizing levers. The inner ends of the equalizing levers have vertically extending portions which terminate in the laterally extending portions which rest upon the half round pivot pins 25. Not only is the spring cap 17 guided in its vertical movements by the H-shaped beams, but it is also guided by wall portions 30 formed integrally with the side frame. These wall portions 30 also directly guide the relative vertical movements of the side frame and the journal box 12. The arm portions 18 of the spring cap 17 are provided with pockets 31 for the reception of springs 32 which extend in an oblique direction diverging upwardly and outwardly from each other. More specifically speaking, these springs 32 respectively extend at right angles to a line connecting the pivot points 27 and 25 of the equalizing levers. These springs are directly engaged by the equalizing beam 14.

24 and as a matter of fact, the equalizing beam rests directly upon said springs, said springs being compressed a predetermined amount, for example $\frac{1}{2}$ " under the weight 5 of the truck when the equalizing beam 24 is brought down into engagement with the spring cap 17. As a result thereof the equalizing beam 24 is maintained in its normal horizontal position, or if moved therefrom is 10 quickly returned thereto. These springs 32 have an additional function in that they have a snubbing action upon the equalizing levers 26. These springs 32 have an initial compression equal to the movement of the 15 ends of the equalizing levers from the normal position and when so compressed have a rated capacity sufficient to overcome the friction at pivot points 23 and 25.

It is my intention to cover all modifications 20 of the invention falling within the spirit and scope of the following claims.

I claim:

1. In a railway car, the combination of an intermediate journal box, springs carried 25 thereby, a spring cap bridging said springs, an equalizing beam pivotally mounted on said spring cap, and springs interposed between said spring cap and equalizing beam for maintaining the equalizing beam in its 30 normal horizontal position.

2. In a railway car truck, the combination of an intermediate journal box, springs carried thereby, a spring cap bridging said springs, an equalizing beam pivotally mounted 35 on said spring cap, and means interposed between said spring cap and equalizing beam for maintaining the equalizing beam in its normal horizontal position.

3. In a railway car truck, the combination 40 of an intermediate journal box, resilient means carried thereby, a spring cap mounted on said resilient means, an equalizing beam pivotally carried by said spring cap, equalizing levers operatively connected to said 45 equalizing beam and having a pivotal relation with respect thereto, and means acting upon said equalizing levers and beams for overcoming friction at pivot points and for

maintaining the equalizing beam in its normal horizontal position.

4. In a railway car truck, the combination 50 of an intermediate journal box, springs carried thereby, a spring cap bridging said springs, an equalizing beam pivotally carried by said cap, springs carried by said 55 spring cap and interposed between the latter and the beam, and equalizing levers operatively connected to said equalizing beam and having pivotal relation with respect thereto, the springs carried by said cap extending at 60 right angles to a line run through the pivotal points of said equalizing levers for overcoming friction at the pivot points and for maintaining the equalizing beam in its normal 65 horizontal position.

5. In a railway car truck, the combination 70 of a side frame, an intermediate journal box, springs carried thereby, a spring cap bridging said springs and having a relative movement with respect to the side frame, an equalizing beam carried by said spring cap, means interposed between said spring cap and beam for maintaining the equalizing beam in its normal horizontal position, and means for guiding the spring cap in its relative 75 movements.

6. In a railway car truck, the combination 80 of a side frame having spaced walls, separate guide members secured between said walls, and equalizing mechanism including a movable spring cap guided in its relative movements with respect to said side frame by said guiding members.

7. In a railway car truck, a side frame 85 having spaced side walls and a top wall, the latter having an opening therethrough for the reception of equalizing mechanism.

8. In a railway car truck, a side frame 90 having an opening in the top thereof, and equalizing mechanism parts which are insertible through said opening for placing said parts in operative position.

Signed at Chicago, Illinois, this 6th day of July, 1921.

JOHN A. LAMONT.
